Primary Examiner — Ricky Pham*(74) Attorney, Agent, or Firm* — Vincent K. Gustafson; Jenkins, Wilson, Taylor & Hunt, P.A.(57) **CLAIM**

The ornamental design for a chair, as shown and described.

DESCRIPTION

FIG. 1 is a perspective view of a chair showing my design; FIG. 2 is a magnified perspective view of a portion of the chair according to circumscribing line 2 shown in FIG. 1; FIG. 3 is a front elevation view of the chair; FIG. 4 is a rear elevation view of the chair; FIG. 5 is a left side elevation view of the chair; the right side elevation view being a mirror image of the left side elevation view; FIG. 6 is a magnified left side elevation view of a portion of the chair according to circumscribing line 6 shown in FIG. 5; FIG. 7 is a top plan view of the chair; and, FIG. 8 is a bottom plan view of the chair.

The broken lines showing is included for the purpose of illustrating environment of the design and forms no part of the claimed design.
